COMBINED ASH TRAY AND CIGARETTE BOX OR SIMILAR ARTICLE

Jacob O. Trautwein, Chicago, Ill.

Application November 23, 1953, Serial No. 27,727

Term of patent 7 years

(Cl. D85—2)

To all whom it may concern:

Be it known that I, Jacob O. Trautwein, a citizen of the United States, residing at Chicago, in the county of Cook and State of Illinois, have invented a new, original, and ornamental Design for a Combined Ash Tray and Cigarette Box or Similar Article, of which the following is a specification, reference being had to the accompanying drawings, forming a part thereof.

In the drawings:

Fig. 1 is a perspective view of a combined ash tray and cigarette box or similar article showing my new design;

Fig. 2 is a top plan view thereof; and

Fig. 3 is a side elevational view thereof.
The lighter shown in broken lines is for illustrative purposes only.

I claim:

The ornamental design for a combined ash tray and cigarette box or similar article, substantially as shown and described.
